UNITED STATES PATENT OFFICE

1,997,663

GUTTER HANGER

Henry E. Usinger, Pitman, N. J., assignor to Berger Bros. Company, Philadelphia, Pa., a corporation of Pennsylvania

Application November 6, 1931, Serial No. 573,387

4 Claims. (Cl. 108—29)

This invention relates to an improvement in gutter hangers and more particularly relates to a hanger for double bead gutters.

The hanger in accordance with this invention 5 is adapted for support of gutters or eaves troughs such as are provided on buildings.

The hanger in accordance with this invention comprises essentially a strap member adapted to 10 embrace the gutter and engage with itself, the strap member being so formed that in engagement with itself it may be drawn into snug engagement with the gutter including the beads thereof, and being provided with a member for attachment to the roof of a building.

15 More particularly the hanger is provided with specially shaped portions for engagement with the beads of a gutter and at the point of engagement with itself, it is formed so that when tightened up around a gutter the bead engaging portions 20 and the hanger as a whole will be drawn into snug engagement.

Having now indicated in a general way the 25 nature and purpose of this invention, I will proceed to a detailed description thereof with reference to the accompanying drawing, in which:

Fig. 1 is a perspective view of a gutter hanger embodying this invention.

Fig. 2 is a sectional view of a double bead gutter with the hanger shown in Figure 1 in place.

30 Fig. 3 is a sectional view on line 3—3, Figure 2.

Fig. 4 is a side view of the subject of Figure 2, in the direction of the arrow 4, Figure 2.

Figs. 5 and 6 are perspective views of modified 35 forms of the engaging ends of the strap.

Referring more particularly to Figure 1, the hanger comprises a bridge portion *a*, bead engaging portions *b*, *b*, a band portion *c* and an end portion *d*, the end portion *d* being slotted as at *e* for the reception of the end portion *c* and at its 40 free end being bent outwardly at an angle as shown at *f*.

The bridge portion *a* may be of any desired 45 shaped in cross section, and may be, for example, as shown in Figure 3, of substantially channel section and provided with a reinforcing rib *g*. A member *h* is pivotally secured to the bridge member and is adapted to be secured to the roof of a building, as by nailing, for the support of the hanger.

50 The bead engaging portions *b*, *b* are formed as shown in Fig. 1, and are slotted as at *i*, *i* to promote ease in conforming them to the beads of the gutter. At the juncture of the bead engaging portions with the band *c* and end portion *d*, the material of the hanger is bent or flared in-

wardly at its edges, as shown at *j*, *j*, Figures 1 and 4.

Referring now to Figures 5 and 6, the modification shown in Figure 5 comprises provision for the end of the band portion *c*' to engage in the slot *i*' in the bead engaging portion *b*' having a free end portion *d*'; while the modification shown in Figure 6 comprises the formation of a boss *k* at the free end of end portion *d*'', adjacent to the slot *e*', by distorting or bending outwardly the body of the end portion instead of bending or distorting the end as described with reference to Figure 1.

In use the hanger is laid on a gutter with the bridge portion *g* between the beads, which will 15 place the bead engaging portions *b*, *b* on the beads. The bridge portion will act to brace the gutter. The bead engaging portion opposite to end portion *d* is then conformed to the bead, its conformance being facilitated by the inwardly flared portions *j*, *j*' at the junction of the bead engaging portion with the band *c*.

The band *c* is then passed beneath the gutter and through slot *e* in end portion *d*. The band is then bent downwardly and drawn up tight 25 against the under side of the gutter. As the band *c* is drawn up, it forces the end portion *d* toward the gutter and, acting on the outwardly turned end *f*, forces the lower portion of the adjacent bead engaging portion up into conformance 30 with the bead, conformance being facilitated by the inwardly flared portions at the juncture of the bead engaging portion and the end portion *d*.

In the modification shown in Figure 6 the boss 35 *k* operates as does the outwardly bent end *f*, while in the modification shown in Figure 5 the inwardly flared portions *j*, *j* facilitate conformance of the bead engaging portion on drawing up of the band portion through slot *i*.

40 What I claim and desire to protect by Letters Patent is:

1. A gutter hanger for double bead gutter comprising, in combination, a strap including a bridge, gutter bead engaging portions at opposite 45 ends of the bridge, a band extending from one of the bead engaging portions and a slotted end portion adapted for interengagement with the band joined to the other bead engaging portion, the end portion being distorted outwardly adjacent the slot therein.

2. A gutter hanger for double bead gutter comprising, in combination, a strap including a bridge, gutter bead engaging portions at opposite 50 ends of the bridge, a band extending from one of 55

the bead engaging portions and a slotted end portion adapted for interengagement with the band joined to the other bead engaging portion, the end portion being distorted outwardly adjacent its free end and the hanger being flared inwardly adjacent its edges at the juncture of the bead engaging portions and the band and end portion respectively.

3. A gutter hanger for double bead gutter comprising, in combination, a strap including a bridge, gutter bead engaging portions at opposite ends of the bridge, a band extending from one of the bead engaging portions and a slotted end portion adapted for interengagement with the band joined to the other bead engaging portion,

the hanger at the juncture of the end portion with the bead engaging portion being flared inwardly and the end portion being distorted outwardly between the slot therein and its free end.

4. A gutter hanger for double bead gutter comprising, in combination, a strap including a bridge, gutter bead engaging portions at opposite ends of the bridge, a band extending from one of the bead engaging portions and a slotted end portion adapted for interengagement with the band joined to the other bead engaging portion, the end portion being distorted outwardly between the slot therein and its free end.
